BY
Richard B. Owen ATTORNEY.

UNITED STATES PATENT OFFICE.

WILLIAM E. OLSON, OF STEVENS POINT, WISCONSIN.

GAME.

Application filed March 18, 1921. Serial No. 453,232.

To all whom it may concern:

Be it known that I, WILLIAM E. OLSON, citizen of the United States, residing at Stevens Point, in the county of Portage and State of Wisconsin, have invented certain new and useful Improvements in Games, of which the following is a specification.

The invention relates to games for amusement and recreation and has for its particular object to provide a game involving the element of skill as well as chance in the successful playing of same.

An additional object is to provide a game adapted to be played upon a game board or table and including movable game pieces designed to be impelled over a playing surface by means of a shooting stick or cue.

With the above and other objects in view, the invention may be said to reside generally in the details of construction, combination and arrangement of parts as will be herein-after more fully pointed out and described, reference being had to the accompanying drawings, wherein—

25 Figure 1 is a top plan view of the invention, and

Figure 2, a transverse cross-sectional view thereof.

Corresponding and like parts are referred to in the following description and indicated in the several views of the drawings by like reference characters.

The game is adapted to be played upon a table or game board 1 having an oblong 35 rectangular surface made smooth, and covered, if desired, with suitable material, such as billiard cloth, and provided adjacent the sides and ends with rubber cushions 2 that form a rebounding foil from which the game pieces may be deflected. At the center of the table a pair of laterally spaced parallel guides 3 and 4 are provided and form a race-way through which the game pieces are adapted to be deflected as indicated by dotted 40 lines in Figure 1. The game board is provided upon its under side with supporting lugs 5 adjacent each corner, these lugs serving to hold the game board firm and steady during the playing of the game.

50 The game pieces are, preferably, hard elastic balls of which as many as desired may be

used. These game pieces are manually impelled across the playing surface by means of a shooting stick or cue 6; the object being to drive one ball against another one or a 55 combination of them, so that the objective ball will be projected against the cushioned edges of the game board.

In the playing of the game with only two game pieces, one of them constitutes the cue ball 7 and the other an objective ball 8. The object of the game is to drive the objective ball through the raceway between guides 3 and 4 by causing it to rebound from the cushion. Consequently, in the playing 60 of the game, the ball 7 is struck by the cue stick 6 in such a manner as to drive ball 8 so that it shall carom or rebound from the cushioned edges 2, ostensibly to enter between and pass through guides 3 and 4. Any 65 suitable rules may be adopted for regulating the scoring and playing of the game.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall 70 within the scope of the appended claim.

Having thus described my invention, what I claim as new and desire to secure by Letters Patent is:—

A game of the character described comprising a game board having a substantially oblong shaped playing surface, cushion rails formed on each side of the game board, guide members arranged longitudinally of the playing surface and located centrally thereon, said guide members being spaced from the sides of the game board and arranged parallel to each other, said guide members forming means to receive the game pieces which deflect or rebound from the cushioned 85 rails.

In testimony whereof I affix my signature in presence of two witnesses.

WILLIAM E. OLSON.
